[57] CLAIM

The ornamental design for a handle stick for a confectionery product, as shown and described.

DESCRIPTION

FIG. 1 is a perspective view of a handle stick for a confectionery product showing our new design;

FIG. 2 is a right side elevational view thereof; the left side elevational view being a mirror image thereof;

FIG. 3 is a top plan view thereof;

FIG. 4 is a bottom plan view thereof; and

FIG. 5 is a cross-sectional view thereof on an enlarged scale taken in the direction of line 5—5 on FIG. 1.
